REAMING OR BORING TOOL

Filed April 21, 1926

Frederick A. Litter
INVENTOR.

Edwin R. Litter

ATTORNEY

UNITED STATES PATENT OFFICE.

FREDERICK A. LITTER, OF COLUMBUS, OHIO.

REAMING OR BORING TOOL.

Application filed April 21, 1926. Serial No. 103,581.

My invention relates broadly to a reaming or boring tool and has particular reference to a device for reboring engine cylinders and the like.

The primary object of my invention is the provision of a reaming and boring apparatus that can be disassembled to facilitate handling and attachment and detachment to the engine block of an automobile or other structure. My novel reaming and boring machine is particularly adapted to the reboring of cylinders which have become worn and in which it is desired to substitute larger pistons.

A further object of my invention is the provision of a portable reaming and boring apparatus that is adapted to perform its intended functions without the necessity of removing the engine block or cylinder from the automobile or other parts to which it may be connected.

A still further object of my invention is the provision of a simple and positive mechanism for automatically advancing or feeding-out the cutter head as the boring or reaming progresses.

Other objects of my invention will be explained in the following description and all features are illustrated in the accompanying drawings wherein similar reference numerals designate corresponding parts in the several figures and wherein—

Figure 1 is a vertical side elevational view, partially in section, showing my novel reaming and boring device and the position and nature of its various parts;

Figure 2 is a fragmentary rear elevational view of the device shown in Figure 1;

Figure 3 is a fragmentary sectional perspective view showing the mechanism for feeding-out the cutter head as the reaming or boring progresses;

Figure 4 is a horizontal sectional view taken on line 4—4 of Figure 1 when the center drive shaft is not in place; and

Figure 5 is a view similar to Figure 4 but showing the center drive shaft in operative position.

In the drawings, one illustrative embodiment of my invention is shown as comprising a base structure 1 which is formed with a boss portion 2 and a leveling and attaching portion 3 that is adapted to be secured to an engine block or other structure in such a position that the reamer aligns with the longitudinal axis of the cylinder. The boss

portion 2 is formed with a centrally and longitudinally extending opening 4, and adjacent its top with a recess 5 for a purpose which will hereafter appear.

A shaft 6 is revolvably and slidably mounted in the opening 4 and has a cutter head 7, equipped with cutters or blades 8, removably attached to its lower end. The shaft 6 may be formed with a socket 9 that extends throughout a considerable portion of its length, and in the walls of this socket are provided the substantially opposite slots 10. The members 11 are preferably pivoted within the slots 10 by means of pins 12 and are normally held in the positions indicated in Figures 3 and 4 by suitable springs 13. On the outsides of the members 11 they are threaded as at 14 so that when expanded the threaded portions thereof will project beyond the periphery of the shaft 6 as shown in Figures 1 and 5. Near its top the shaft 6 is provided with a key 15.

Surrounding the shaft 6 is an internally threaded jacket or sleeve 16 that has a portion 17 which extends into the recess 5 formed in the boss portion 2 of the base 1. This jacket is also formed with a lug 18 that engages under stop 19 carried by the base. The stop 19 with its pin 20 effectively prevents longitudinal and rotary movement of the jacket 16 with relation to the base 1. Adjacent its top the jacket 16 may be provided with a recess 21 and an upstanding pin or stop 22 for a purpose to be later explained.

The drive mechanism for the cutter head comprises a shaft 23 which is preferably provided with a cross pin 24 and a pinion 25 that is in mesh with a gear 26 mounted on a shaft 27 that also carries a pinion 28 which meshes with another gear 29 secured to the top of shaft 30. The lower end of shaft 23 is loosely journaled in the top of shaft 30 as is clearly shown in Figure 1. The drive arrangement just described constitutes a reduction gearing and makes possible the use of a comparatively small electric motor or the like for driving the reamer. The shaft 30 telescopes with the socket 9 of shaft 6 and has a key-way 31 that engages with the key 15 carried by shaft 6. The reduction gearing is enclosed by a case 32 that has a portion 33 seated within the recess 21 of the jacket 16. It also has a lug 34 which abuts against the stop 22 to prevent relative turning movement between the case and jacket

16. When the shaft 30 is inserted into socket 9 it forces the threaded parts 14 of members 11 into engagement with the threads on the interior of jacket 16, and when withdrawn 5 it allows the springs 13 to move members 11 into their normal or inoperative position.

In the operation or use of my invention the gear case 32 with shaft 30 may be lifted out of connection with the other parts and 10 the jacket 16 removed from the base to reduce the weight to be handled while positioning the base and reamer with relation to the cylinder to be operated upon. The base 1 may be attached directly to the engine 15 block or other structure in such a position that the cutter head aligns with the longitudinal axis of the cylinder. When the base has been so attached, the jacket 16 may be placed over the shaft 6 and its lug 18 engaged with the pin 20 under the stop 19. The third part comprising the gear case 32 and shaft 30 may now be connected to the parts already assembled by telescoping the shaft 30 with the socket 9 and revolving 20 until the lug 34 abuts against stop 22.

When the parts have been connected as above described, power may be applied to the shaft 23 by any suitable means, as for instance a small electric motor. The motion of the shaft 23 will be communicated to the shaft 30 through the reduction gearing previously described. The shaft 30 through its key way 31 and the key 15 will revolve the shaft 6 and so turn the cutter head 7. As has been stated, when the shaft 30 is inserted into the socket 9 the threaded portions of the members 11 are forced outwardly into engagement with the threads on the inside of jacket 16, as best shown in Figures 1 and 5. Since the jacket 16 is secured against rotary and longitudinal movement by reason of the engagement of its lug 18 with the pin 20, it results that the shaft 6, when rotated by shaft 30, will also be advanced downwardly to thrust the cutter head further into the cylinder as the cutting or boring progresses. The threads 14 on the members 11 and the cooperating threads on the inside of the jacket 16 are such that the feeding-out or downward projection of the cutter head 7 progresses at a rate suitably proportioned to the rate of cutting of the cutters 8. The reborning of a cylinder by my novel apparatus may be accomplished without removing or disconnecting the engine block or cylinder from the other parts to which it may be connected and so obviates the necessity for these laborious and costly operations. When the boring or reaming 50 has been completed the various parts of the apparatus may be disassembled and removed to another cylinder.

From the preceding description, it will be obvious that I have provided a simple, compact and portable apparatus for the pur-

pose set forth, which has a minimum number of parts and is substantially constructed. It will, furthermore, be obvious that I have provided an extremely simple and positive device for advancing the cutter head into the cylinder as the boring or reaming progresses.

Claims:

1. Reaming or boring apparatus comprising in combination, a cutter head, a shaft connected to said cutter head, an internally threaded sleeve surrounding said shaft and means carried by said shaft and adapted to be expanded into engagement with the threads on said sleeve.

2. In a device of the class described, the combination of a tubular tool carrying shaft, driving means adapted to telescope with said shaft and means rendered operative by the telescoping of said driving means and shaft for projecting said shaft longitudinally.

3. In a device of the class described, the combination of a tool carrying shaft, an internally threaded sleeve enclosing said shaft, threaded means mounted in slots in said shaft and driving means adapted to move said threaded means into engagement with the threads in said sleeve.

4. In a reaming and boring apparatus, the combination of a tool carrying shaft, an internally threaded sleeve enclosing said shaft, threaded means carried by said shaft and driving means adapted to cooperate with said shaft, said driving means being effective to move said threaded means into engagement with the threads in said sleeve.

5. Cylinder reborning apparatus comprising a tool carrying shaft, threaded members carried by said shaft, an internally threaded sleeve surrounding said shaft and drive means adapted to cooperate with said shaft, said drive means being adapted to revolve said shaft and to force said threaded members into engagement with the threads on said sleeve whereby said shaft will be moved longitudinally as it is revolved.

6. A reaming or boring apparatus comprising a shaft having a hollow portion, slots in said shaft, a cutter head mounted upon the end of said shaft that is remote from said hollow portion, threaded collapsible and expansible members mounted in said slots, an internally threaded sleeve surrounding said shaft and a shaft adapted to be projected within the hollow portion of said first named shaft to move said collapsible and expansible members into engagement with said sleeve and means for revolving said first named shaft.

7. In a reaming and boring apparatus, the combination of a driven shaft, a cutter head carried by said driven shaft, a driving shaft adapted to cooperate with said driven shaft, and collapsible and expansible means for connecting said shafts, said collapsible

and expandible means being rendered effective by the cooperative positioning of said shafts for moving said driven shaft along its longitudinal axis.

5 8. In a reaming or boring apparatus, a driven shaft having a hollow portion, a cutter head carried by said driven shaft, slots in said shaft, collapsible and expandible members mounted within said slots, a sleeve

surrounding said shaft and a drive shaft 10 adapted to be projected into said first named shaft to move said collapsible and expandible members into operative relation with said sleeve to connect said shafts.

In testimony whereof I hereby affix my 15 signature.

FREDERICK A. LITTER.
